UNITED STATES PATENT OFFICE.

AUGUSTE CHANARD, OF RUEIL, FRANCE.

CARBURETOR.

Application filed July 23, 1924, Serial No. 727,845, and in France July 28, 1923.

The present invention has for its object an improvement in carburetors for internal combustion motors, of that type comprising a series of carbureting chambers opening 5 into a common header, and a controlling or obturating device which permits of the number of carbureting chambers put into action being varied at will.

The invention is clearly illustrated in the 10 accompanying drawings, in which; Fig. 1 is a longitudinal section of the improved carburetor; Fig. 2 is a plan view, partly in horizontal section made at the level of the spraying orifices; Fig. 3 is a cross section made according to line A—A of Fig. 1; Fig. 4 is a 15 rear view.

As illustrated in the drawings, the present carburation apparatus comprises a series of carburetion chambers a , a^1 , a^2 , a^3 , 20 a^4 , a^5 , a^6 , a^7 , a^8 , completely independent from each other, freely communicating at one of their ends with the atmosphere, and opening at their other end in a casing or header b ; the latter is provided at its end with a flange 25 c on which is secured the pipe which connects it with the suction manifold of the engine.

Each of these carburetion chambers preferably has internally, the shape of a Venturi tube, according to the profile illustrated in 30 Fig. 1, and has an excessively reduced cross section; the first chamber, adapted as indicated hereafter to feed the engine in the case of slow speed running, has, in its throttled portion, a diameter of about two millimeters; 35 the diameter of the throttled portion of the other carburetion chambers can have about six millimeters.

In the throttled portion of each of the carburetion chambers a , a^1 , a^2 . . . opens a tube 40 d , d^1 , d^2 . . . at the end of which is mounted, as shown in Figs. 1 and 3, a plate provided with a calibrated hole e , e^1 , e^2 . . . having for instance a diameter of 5 tenths of a millimeter; each of the tubes d , d^1 , d^2 . . . is coupled to a pipe f , f^1 , f^2 . . . connecting it to the gasoline reservoir g which can be placed on the vehicle lower than the carburetion apparatus at any distance and at any level.

Within the casing b is introduced with 50 slight friction, a valve h , in the form of a cylindrical body having a bore h' and which body can be moved in the longitudinal direction either directly by hand, or through the medium of any control device.

55 In one of its extreme positions (Fig. 1) this valve body uncovers solely the first car-

buration chamber a corresponding, as above stated, to slow speed running.

By moving this obturator in the direction of the arrow shown in Fig. 1, the various carburation chambers a^1 , a^2 . . . will be successively put in function, in variable number according to the power required from the engine.

In order to permit, particularly in case of slow speed running, an additional admission of air, for the purpose of varying for instance the speed of the engine from 150 to 900 revolutions, the valve body h has its bore h' enlarged as at h^2 and this enlarged portion slidably receives a secondary slide valve i , the body of which is also partially bored, the outer end being closed and provided adjacent the closed projecting portion with a series of holes j through which air 75 enters from the atmosphere and passes through the bore in the secondary valve body and thence through the aligning bore of the main valve body into the casing b .

By moving the slide valve i in the direction 80 of the arrow shown in Fig. 1, the air inlet holes j will thus be successively uncovered and it will thus be possible to vary at will the inlet cross section of the additional air which will have to be added, according to the desired speed, to the carbureted air supplied by the first carburetion chamber.

The operation of this carburetion apparatus is as follows:

For slow speed running, the valve h , 90 brought to the position shown in Fig. 1, uncovers only the first carburetion chamber a , as above stated.

Owing to the very small cross section of the throttled portion of this carburetion chamber, on the one hand the air from the exterior drawn in by the partial vacuum created within the engine, passes through this chamber at a very high speed and thus produces the suction of the gasoline supplied by the calibrated hole e always in the required proportion; on the other hand, this air and gasoline intimately mix together and supply a carbureted mixture sufficiently rich for always ensuring an instantaneous starting of the engine.

By operating the slide valve i , the proportion of additional air admitted through the holes j can be increased and the speed of running can pass from 150 to 900 revolutions.

For progressively increasing the power of 110 the engine, it suffices to move the obturator h in the direction of the arrow shown in Fig. 1,

so as to successively put in action the various carburation chambers $a^1, a^2 \dots$ Under the action of the partial vacuum created by the engine in these various carburation chambers, 5 in each of them is produced a suction of air and gasoline which intimately mix together, as above stated, owing to the small diameter of these chambers, before entering into the casting b .

10 Each chamber $a^1, a^2 \dots$ supplies therefore a homogeneous carbureted mixture of approximately constant composition; according to the number of chambers put in action, the volume of carbureted air supplied to the engine 15 can thus be regulated at will.

For slowing down the speed of the engine, it suffices to move the valve h in the reverse direction so as to successively put out of action the unitary carburetors.

20 In case this valve h is suddenly brought back to its initial position, corresponding to slow speed running, it is to be noted that owing, on the one hand, to the small mass or body of gasoline drawn in in each carburetor cham-

ber in action and, on the other hand, to the successive obturation of the unitary carburetors, no outflow of gasoline can take place in the latter by effect of inertia, thus doing away with the risks of fire by back firing.

Claim:

25 A throttle valve for carburetors comprising a valve body reciprocating in an opening in the carburetor casing to control the passage of the mixture through said carburetor, said body having a longitudinal bore, a secondary valve body slidably mounted in the bore and also provided with a bore and with additional passages communicating with the bore and normally covered by the main valve body 30 but adapted to be uncovered upon the independent movement of the secondary valve body to permit of the passage of additional air through said valve bodies, substantially as and for the purposes set forth.

35 The foregoing specification of my carburetor, signed by me this 8th day of July, 1924.

40 AUGUSTE CHANARD.
